DESIGN FOR A DOLL OR SIMILAR ARTICLE

Maurice Marossi, New York, N. Y., assignor to Margroson Corp., New York, N. Y., a corporation of New York

Application November 29, 1944, Serial No. 116,599

Term of patent 3½ years

(Cl. D34—4)

To all whom it may concern:

Be it known that Maurice Marossi, citizen of Czechoslovakia and resident of New York city, in the county of New York and State of New York, has invented a new, original, and ornamental Design for a Doll or Similar Article, of which the following is a specification, reference being had to the accompanying drawing, forming part thereof, and in which,

Fig. 1 is a front view of the doll, embodying
my new design;

Fig. 2 is a side view thereof; and
Fig. 3 is a rear view thereof.

I claim:

The ornamental design for a doll or similar article, substantially as shown.

MAURICE MAROSSI.
